UNITED STATES PATENT OFFICE.

MAUDE SIEGEL, OF NEW YORK, N. Y., ASSIGNOR TO FRANKLIN SIMON & COMPANY, INC., OF NEW YORK, N. Y., A CORPORATION OF NEW YORK.

DESIGN FOR A DRESS.

Application filed September 17, 1928. Serial No. 28,178. Term of patent 3½ years

To all whom it may concern:

Be it known that I, MAUDE SIEGEL, a citizen of the United States, and a resident of the city of New York, borough of Manhattan, in the county of New York and State of New York, have invented the new, original, and ornamental Design for Dress of which the following is a specification.

Reference is had to the accompanying drawing, forming part thereof, wherein

in Figure 1, the same being illustrated on a figure indicated by dotted lines;

I claim:

The ornamental design for a dress substantially as shown and described.

Signed at New York, in the county of New York and State of New York, this 14 day of September, A. D. 1928.

MAUDE SIEGEL.
